UNITED STATES PATENT OFFICE

139,994

DESIGN FOR A WEDDING DRESS ENSEMBLE

Josephine Azzaro, New Haven, Conn.

Application September 27, 1944, Serial No. 115,484

Term of patent 3½ years

(Cl. D3—26)

To all whom it may concern:

Be it known that I, Josephine Azzaro, a citizen of the United States, residing in New Haven, in the county of New Haven and State of Connecticut, have invented a new, original, and ornamental Design for a Wedding Dress Ensemble, of which the following is a specification, reference being had to the accompanying drawing, forming part thereof, in which

Fig. 1 is a face view of a wedding dress ensemble embodying my invention;

Fig. 2 is a rear view of the same;
Fig. 3 is a fragmentary rear view of the upper part of the dress portion of the ensemble; and
Fig. 4 is a plan view of the veil of the ensemble on an enlarged scale.

I claim:

The ornamental design for a wedding dress ensemble, substantially as shown.

JOSEPHINE AZZARO.
